UNITED STATES PATENT OFFICE.

JOSEPH GOULBOURN, OF LEICESTER, ENGLAND, ASSIGNOR TO UNITED SHOE MACHINERY COMPANY, OF PATERSON, NEW JERSEY, A CORPORATION OF NEW JERSEY.

DASH-POT MECHANISM.

1,240,196.

Specification of Letters Patent. Patented Sept. 18, 1917.

Application filed December 6, 1913. Serial No. 805,159.

To all whom it may concern:

Be it known that I, JOSEPH GOULBOURN, a subject of the King of England, residing at Leicester, Leicestershire, England, have invented certain Improvements in Dash-Pot Mechanisms, of which the following description, in connection with the accompanying drawings, is a specification, like reference characters on the drawings indicating like parts in the several figures.

This invention relates to improved dashpot mechanism for use in machinery for retarding the movement of a part of the machine, as for example, a power operated lever to which motion is transmitted through a spring and from which the load is released while the spring is under a tension which would tend to cause the lever to move past its normal stopping position and do damage. Another and more important use to which the novel dashpot of this invention has been put is to retard the power-effected movement of a lever or the like operated as suggested, whereby power is stored in the transmission spring and is gradually given out through the lever as the dashpot permits.

A feature of the invention resides in a novel construction and arrangement of relatively movable members, one having a chamber for the reception of a fluid and the other being shaped to serve as a piston in said chamber, together with means providing a restricted passage in communication with the chamber to permit a retarded flow of the fluid upon a relative movement of said member. In the construction shown an outer member is provided, having a chamber of relatively small diameter in its lower portion, and an inner member held substantially stationary is arranged to serve as a piston in the smaller portion of the chamber and is provided with a passage for conducting the fluid from the lower to the upper portion of the chamber when the outer member is raised.

Further features of the invention reside in novel means for controlling the flow of the retarding fluid, and in a novel construction and arrangement affording an initial unretarded relative movement of the portions of the dashpot mechanism.

These and other features of the invention

will now be more particularly described in connection with the accompanying drawings and will then be pointed out in the claims.

55

Figure 1 is a side elevation of part of a machine in which a lever is operated as above described with a preferred construction of the new dashpot mechanism applied thereto;

Fig. 2 is a sectional side elevation of a portion of the machine drawn to a larger scale than Fig. 1, the updrawing lever being shown in its raised position;

Fig. 3 is a view similar to Fig. 2, the updrawing lever being shown in its lowered position, and

Fig. 4 is a section on the line 3—3 of Fig. 2 looking in the direction of the arrow.

The embodiment of the invention herein shown comprises an outer member or plunger 1 which is mounted to slide within a bore 2 formed in a boss on the framework 3 of the machine. The plunger is hollow to hold oil or other fluid and the lower portion 4 of the chamber in the plunger is of smaller diameter than the upper portion 5. Secured to the frame 3 and extending within the bore 2 is a cylindrical inner member 6 which is shaped to serve as a piston in the lower portion of the chamber in the plunger. The upper end of this member is provided with a reduced barrel-shaped portion 8 which is received loosely within a recess 10 formed in the frame, the member 6 being held in place by a screw 12 which passes through the boss and enters loosely a hole in the barrel-shaped portion of the member 6. This method of attaching the member 6 to the frame allows the member to rock slightly for a purpose which will be hereinafter explained.

Surrounding the member 6 is a coiled spring 15 which bears at its upper end against a flange 14 projecting from the member 6 and at its lower end bears against a shoulder 16 at the junction of the upper and lower portions of the chamber in the plunger 1. This spring normally forces the plunger outwardly in the bore 2 and holds it in contact with a boss 17 on the upper side of the updrawing lever 18.

The member 6 is provided with an internal passage 20 which extends longitudinally thereof. The upper portion 21 of this pas-

sage is enlarged diametrically and from this portion extend lateral passages or ports 23 which communicate with the enlarged or upper portion 5 of the chamber in the plunger 1. The member 6 is also provided with a valve spindle 25 which is screwed therein at its upper end, as shown in Fig. 2, and is provided with a reduced portion 24 which is positioned in the enlarged portion 21 of the passage 20. The reduced portion 24 of the valve spindle is of slightly less diameter than the enlarged portion 21 of the passage, so as to allow fluid to pass between the walls of the passage and the spindle and out through the ports 23, as will be hereinafter explained.

A passage 26 is formed in the frame which when the plunger 1 is in an extreme outer position, lower than shown in Fig. 3, communicates through the bore 2 with the portion 5 of the chamber in the plunger. This passage is provided for the purpose of allowing oil or any other suitable liquid to be poured into the chamber.

25 The dashpot device is preferably arranged at an angle to the horizontal, as shown, so that the oil will flow into the lower portion 4 of the chamber in the plunger when the member 6 is removed from that portion of the plunger.

Before the beginning of the updrawing movement of the lever 18, which is fulcrumed at 19 and operated by power driven mechanism through spring 21, the plunger 1, which as previously mentioned is held in engagement with the lever by means of the spring 15, is situated as shown in Fig. 3 with respect to the member 6, that is, with the lower end of the member 6 positioned in the enlarged or upper portion 5 of the chamber in the plunger 1 and some distance above the lower or smaller portion 4 of the chamber. When the updrawing movement of the lever commences the plunger 1 will be forced inward in the bore 2 and moved toward the member 6 and continued inward movement of the plunger will cause the member 6 to extend into the lower portion 4 of the chamber and cause the oil contained in the chamber to be forced through the passage 20 past the valve spindle 25 and out through the ports 23. The oil will thus be forced gradually into the portion 5 of the chamber, and when the updrawing lever moves in a reverse direction and the lower portion 4 of the chamber in the plunger is moved by gravity and the spring 15 away from the cylindrical member the latter is completely withdrawn from the portion 4 of the chamber as shown in Fig. 3, and the oil will then quickly flow back into the lower portion of the chamber and be ready for the next lever retarding operation of the dashpot. The dashpot is preferably, although not necessarily, so constructed that the member 6 is

normally separated a substantial distance from the mouth of chamber 4, as shown in Fig. 3, whereby retardation of the movement of the plunger, by reason of the slow passage of the oil through channels 20, 21, 23, 70 does not begin until the plunger has completed a part of its stroke.

From the foregoing it will be understood that the updrawing movement of the lever is checked or retarded by reason of the necessarily slow passage of the oil out of chamber 4; also it will be understood that if the lever is thereafter freed from its load the device will act as a buffer and prevent shock to the parts of the machine. In order to vary the resistance afforded to the updrawing motion, the valve spindle can be adjusted longitudinally and be locked in its position of adjustment by milled nuts 30. This adjustment varies the position of the valve spindle in the enlarged portion of the passage in the cylindrical member and increases or decreases the resistance offered to the passage of the oil, and consequently the rate of movement of the updrawing lever can be increased or decreased.

The aforementioned manner of mounting the member 6 in a recess 10 formed in the frame so as to allow rocking movement is adopted so as to enable the member to take up its correct position relatively to the lower portion 4 of the chamber in the plunger 1 and thus insure that the member shall enter said lower portion. The lower end of the member 6 is rounded off so that should it engage the shoulder 16 it will slide off and be directed into said lower portion. The flange 14 on the member 6 is arranged to bear against the end surface 32 of the bore 2 and this flange serves to take up the end 105 thrust of the member.

In order to direct oil, after it has passed through the ports 23, into the chamber in the plunger 1 there is provided at the top of the plunger a downwardly and inwardly projecting flange 34. This flange also serves to prevent oil from being thrown out of the plunger into the upper part of the bore 2 and so assists in preventing waste of oil by leakage. If desired, a non-return valve 115 may be provided in the passage 26 so as to minimize any leakage through this passage.

Having now described the invention and explained in what manner the same may be used, I claim as new and desire to secure by Letters Patent of the United States:

1. A dashpot mechanism comprising a plunger having a chamber open at its upper end and adapted to contain liquid, a member extending through said open end 125 and fitting into said chamber and having a discharge passage, and a frame or support in which said member is fastened and which has a bore in which the plunger is movable, said parts being so constructed and arranged 130

that during the rise of the plunger the liquid will be forced through the passage in said member.

2. A dashpot mechanism comprising a plunger having a fluid containing chamber of relatively large diameter in the upper portion of the plunger and of smaller diameter in the lower portion of the plunger, a substantially stationary member extending freely through the large part of said chamber and adapted to fit the smaller part of the chamber and having a passage from its lower end upwardly, and a port located to cause said passage to communicate with the larger part of the chamber in the plunger as the plunger is raised.

3. A dashpot mechanism comprising a plunger having a fluid containing chamber of relatively large diameter in the upper portion of the plunger and of smaller diameter in the lower portion of the plunger, a substantially stationary member extending freely through the larger part of said chamber and adapted to fit the smaller part of the chamber and having a passage from its lower end upwardly, a port located to cause said passage to communicate with the larger part of the chamber in the plunger as the plunger is raised, and a valve spindle fitting the upper portion of said passage and having a reduced portion adapted to be adjusted to extend more or less past the port.

4. A dashpot mechanism comprising a frame or support having a bore, a hollow plunger guided in said bore, the lower portion of the chamber in the plunger being of smaller diameter than the upper portion, and a member held longitudinally stationary but laterally rockable in the frame or support to permit it to find and freely enter the smaller portion of the chamber in the plunger, said member being shaped to fit in the smaller portion of said chamber and provided with a passage extending from its lower end and communicating with the larger portion of the chamber in all relative operative positions of the plunger and member.

5. A dashpot mechanism comprising a frame or support having a bore, a hollow plunger guided in said bore, the lower portion of the chamber in the plunger being of smaller diameter than the upper portion, and a member held longitudinally stationary in the frame or support, a spring arranged to move the plunger in one direction in said bore, said member having an internal passage forming a restricted communication between the lower portion of the plunger chamber and the upper portion thereof to cause fluid in the chamber to retard and delay the movement of the plunger into said bore.

6. A dashpot mechanism comprising a plunger having a fluid containing chamber

of relatively large diameter in the upper portion of the plunger and of smaller diameter in the lower portion of the plunger, a substantially stationary member extending freely through the larger part of said chamber and adapted to fit the smaller part of the chamber and having a passage from its lower end upwardly, a port located to effect communication between said passage and the larger part of the chamber in the plunger as the plunger is raised, and a passage formed in the frame or support and located so as to be closed by the plunger in all working positions of the latter and to communicate with the bore in the frame and therethrough with the chamber in the plunger to supply liquid to the plunger chamber when the plunger is lowered to an abnormal position.

7. A dashpot mechanism comprising an outer member 1 having a fluid containing chamber 4 and a chamber 5 of larger diameter opening thereinto, an inner member 6 having a part fitted to the chamber 4 to expel the fluid therefrom and a restricted passage through which the fluid must escape from chamber 4 into chamber 5 whereby relative approach of the two members is retarded, and a spring 15 arranged to withdraw from the chamber 4 into the chamber 5 the part of the inner member which fits the chamber 4 whereby quick refilling of chamber 4 is permitted.

8. A dashpot mechanism comprising an outer member having a fluid containing chamber, an inner member shaped to serve as a piston in said chamber, one of said members having a restricted passage to permit a retarded flow of the fluid from the chamber upon a relative closing movement of the members, and means for positioning said members normally with the inner member at a distance from said chamber to permit a limited unretarded relative movement of the members prior to the entrance of the inner member into the chamber.

9. A dashpot mechanism comprising an outer member having a fluid containing chamber of relatively small diameter in its lower portion and of larger diameter in its upper portion, an inner member shaped to serve as a piston in the lower portion of said chamber and to extend freely through the upper portion of the chamber, one of said members having a restricted passage to permit a retarded flow of the fluid from said lower portion of the chamber to the upper portion upon a relative closing movement of said members, and means for effecting a relative return movement of said members of sufficient extent to open the lower portion of the chamber to the upper portion for the return of the fluid.

10. A dashpot mechanism comprising an outer member having a fluid containing

chamber of relatively small diameter in its lower portion and of larger diameter in its upper portion, an inner member shaped to serve as a piston in the lower portion of said chamber and to extend freely through the upper portion of the chamber, means for guiding the outer member for movement toward and from the inner member, one of said members having a restricted passage to permit a retarded flow of the fluid from the lower portion of the chamber to the upper portion upon a movement of the outer member toward the inner member, and means for effecting a return movement of the outer member of sufficient extent to open the lower portion of the chamber to the upper portion and position said lower portion of the chamber at a distance from the lower end of the inner member.

11. A dashpot mechanism comprising an outer member having a fluid containing chamber, an inner member shaped to serve as a piston in said chamber, said inner member having a passage extending lengthwise thereof and arranged to open into said chamber and a port leading laterally from said passage outside of that portion of the

chamber in which said member acts as a piston, and a valve spindle adjustable 30 lengthwise of said passage to control the flow of fluid through said port.

12. A dashpot mechanism comprising an outer member having a fluid containing chamber, an inner member shaped to serve as a 35 piston in said chamber, said inner member having a passage extending lengthwise thereof and arranged to open into said chamber and a port leading laterally from the outer portion of said passage, said outer portion of the passage being enlarged in diameter, and a valve spindle adjustable lengthwise in said enlarged portion of the passage and having an end portion of reduced diameter arranged to extend past said port and 40 movable toward or from the smaller portion of the passage in the adjustment of the valve.

In testimony whereof I have signed my name to this specification in the presence of 50 two subscribing witnesses.

JOSEPH GOULDBOURN.
